UNITED STATES PATENT OFFICE.

FRANK T. SLOAN, OF NEW YORK, N. Y.

TANK.

1,130,936.

Specification of Letters Patent.

Patented Mar. 9, 1915.

Application filed February 9, 1910. Serial No. 542,878.

To all whom it may concern:

Be it known that I, FRANK T. SLOAN, a citizen of the United States, and a resident of the city of New York, borough of Brooklyn, in the county of Kings and State of New York, have invented certain new and useful Improvements in Tanks, of which the following is a specification.

This invention relates to certain novel and useful improvements in tanks, and more particularly in the construction and arrangement of tanks or baths used in factories and like places to contain shellac, varnish, paint, or other inflammable coating materials. In the use of the tanks referred to, articles of various sorts are dipped into the tank containing the shellac or paint and then laid upon drains which are so arranged in relation to the tank that the drip will flow back into the tank.

The object of my invention is to provide simple and compact means for automatically covering and emptying such tanks in case of fire, thereby preventing explosions, or the spreading of the fire by reason of the ignition of the inflammable material.

In carrying out my invention, it is my object to provide a cover for the tank which may be readily moved away laterally and secured in inoperative position, so that it will not interfere with the dipping operations, which is a desired factor in the work.

Another object is to provide means for automatically returning the cover over and upon the tank when the holding means is released by heat.

Still another object is to provide means whereby the cover may be most conveniently returned upon the tank when the dipping operations have been concluded, thereby lessening the possibility of the tank being left uncovered by negligent employees.

Another object of my invention is to provide automatic means, acting in conjunction with the automatic control of the cover, for emptying the tank. For this purpose, I have provided a valve so constructed as to reduce to a minimum the possibility of the parts becoming clogged by the gumming of the contents of the tank.

Still another object is to combine the whole into one article, so that it will be portable and readily set up and put into operation.

So far as I am aware, I am the first to accomplish these objects by any apparatus

constructed and operating in the manner herein described.

In the accompanying drawings, wherein, by way of illustration, one embodiment of my invention is delineated,—Figure 1 is a side elevation of the tank, the supporting frame and operating parts; Fig. 2 is a plan view of the apparatus with the cover retracted; Fig. 3 is a cross section on line 3—3 of Fig. 2; Fig. 4 is an enlarged cross sectional detail through the tank and valve and pipe connections; Fig. 5 is a similar view, taken on line 5—5 of Fig. 4; and Fig. 6 is a cross section of a building showing, in elevation, my device installed on one of the floors.

Referring now to the accompanying drawings in detail: A represents a side wall and B, B', B², the floors of a building, on one of which floors is represented my apparatus, designated in whole at C, to which is connected the pipe D, which leads to a receiving vessel E, located outside the building, or it may be connected to a sewer pipe or other means of discharge exterior of the building.

The apparatus comprises a supporting frame, consisting of uprights 5, 5^a, 6, 6^a, to which are connected the longitudinal members 7, 7^a, 8, 8^a, and the transverse members 9, 9^a, 10, 10^a, the uprights 5, 5^a and 6, 6^a being rigidly secured to the floor B' by screws 11 passing through offsets 12 on said uprights or in any other suitable manner.

Between the longitudinal members 7 and 8 of the supporting frame I place the tank 13, which is provided with ears 13^a, which are shown secured to the members 7 and 8 by screws 13^b. The tank may be of any desired shape and made of any suitable material, but my preferred form is circular in cross section and made of sheet metal or casting, having perpendicular sides, as at 13^c and a downwardly sloping bottom portion 13^d, having at the center thereof a circular opening 13^e, the edge being beveled as at 13^f to act as a valve-seat for the valve to be hereinafter described. Connected to or made integral with the bottom 13^d is a circular outlet 13^g, threaded to the lower inner edge of which is a short connecting pipe 14, which is threaded to the upper end of a coupling 15, which, at its lower end is threaded to the pipe D.

The coupling 15 is made sufficiently large to house the valve-operating parts shortly to be described.

Arranged to reciprocate within the upper

end of the outlet 13^e is the valve 16, the edge of which is beveled to make a close connection with the valve seat 13^f. Threaded or otherwise secured to the valve 16 is the valve stem 17, which, at its opposite end, is bifurcated as at 17^a, 17^b. Projecting from one side of the valve stem 17 is a horizontally disposed pin 18, the purpose of which will presently appear.

Projecting transversely through the coupling 15 is a rock shaft 19, which rocks in bearings formed in the sides of the coupling. The shaft 19, at or near one end, is provided with an eccentric cam 19^c, which, on the 15 rocking of the shaft 19 is adapted to raise the pin 18. One end of the shaft 19 projects outside the coupling 15, and keyed thereto, by means of the set-screw 19^d is the valve operating lever 19^e, which is itself operated 20 by the weight 19^f. When the weighted lever 19^e is held in a raised position it will be seen that the valve 16 will close by gravity, but the lowering of the lever 19^e rocks the shaft 19 and, with it, the cam 19^c, thereby raising 25 the pin 18 and throwing the valve 16 off its seat 13^f.

Extending longitudinally of the frame of the apparatus, I provide, at each side of the tank 13, an inclined trackway 20, 21, the 30 ends being screwed or otherwise secured to the uprights 5, 5^a, 6, 6^a respectively.

The apparatus further comprises a movable cover for the tank, consisting of the cover plate 22, to which are secured, in any 35 suitable manner, the supports 23, 23^a, 24, 24^a. These supports may be of sheet metal or other suitable material and are angular in form, the upper or horizontally disposed portion being secured to the cover plate 22 40 and projecting outwardly so as to clear the longitudinal members 7 and 8 of the frame, and the perpendicularly disposed portions being provided with wheels 25, 25^a, 26, 26^a, said wheels being grooved and adapted to 45 travel on the inclined trackways 20, 21 respectively. The cover 22 is provided with a hand-hold 27 and a trigger-catch 28.

Extending transversely of the frame of the apparatus I provide a rod 28^a, the ends 50 of which are secured to the uprights 5 and 6. This rod carries a trigger 29, in the form of a bell-crank, comprising the arm 29^a, notched at one end to lock with the catch 28, and the arm 29^b, shown in dotted lines in Fig. 1, the arm 29^b being provided with a stud 29^c. Also connected to the rod 28^a, and held in place thereon by the collar 29^d is the trigger-operating arm 29^e, one end of which encircles 55 the rod 29. The outer portion is wider and heavier than the part just mentioned and is provided with a slot 29^f, within which the stud 29^c of the arm 29^b has limited movement. The parts 29 and 29^b are separated 60 by a collar 29^g.

Connected to the heavy portion of the arm

29^e is a chain 30, which when subjected to strain holds the trigger-operating arm 29^e in an elevated position and likewise the trigger-arm 29^b in contact with the catch 28. From its point of connection with the trigger-operating arm 29^e, the chain 30 passes over an idler pulley 30^a secured to the ceiling above the floor B', thence over an idler pulley 30^b secured to the frame of the apparatus, and thence to a connection with the 70 weighted lever 19^f. The chain 30 is provided with two or more links or connecting pieces 30^c of lead or other suitable material readily fusible at a comparatively low temperature.

The operation of the device will be readily apparent from the foregoing description. With the levers 19^f and 29^e in the positions shown in Fig. 6, the valve 16 is closed, and assuming that the tank is filled and has remained closed during the night, for example, the workman finds, in the morning, all the parts as shown in said figure except that the cover 22 will be in place over the tank as shown in Fig. 3. Desiring to use the tank, 90 he moves back the cover 22, the same moving up the inclined tracks, the catch 28 brushes under the arm 29^a and is secured thereto by the notch therein. It will be seen that the tank may be opened and closed at any time 95 by the workman without disturbing the rest of the apparatus. Assuming now that at the end of the day's work, the operator neglects to close the tank and a fire occurs in the building, the links 30^c immediately 100 fuse on a considerable rise in temperature due to the fire, the chain is parted at those points, the weighted lever 29^e falls, the stud 29^c contacts, at the end of the slot 29^f, with the lever 29^b, depressing the arm 29^b, raising the trigger-arm 29^a and clearing the 105 catch 28. Thereupon, the cover 22 is carried automatically into position over and covering the top of the tank. At the same moment that the chain is severed, the 110 weighted lever 19^f falls, turning the shaft 19 and with it the cam 19^c, which, in turn, raises the pin 18, and, with it, the valve-stem 17, thereby throwing the valve 16 off its seat and opening the outlet from the 115 tank, whereupon all the combustible material therein is quickly carried through the outlet and pipe coupling into the pipe D, and thence to the receiving vessel E or to the sewer.

Having thus described my invention, what I claim is:

1. The combination with a dipping tank having a valved opening and thermostatically controlled means for opening the valve, 125 of inclined rails juxtaposed to said tank, a horizontally disposed cover for said tank, means depending from said cover upon which the latter is maintained in horizontal position while moving laterally upon said 130

- 5 rails toward and away from the tank, and upon which it may be returned on said rails by gravity to close said tank, and thermostatically controlled means for releasably holding said cover at one side of said tank.
- 10 2. The combination with a dipping tank having a valved opening and thermostatically controlled means for opening the valve, of a frame within which the tank is fixed, inclined rails oppositely arranged, a cover provided with depending means for moving on said rails horizontally away from the tank, pivotally mounted counter-balanced means for engagement with said cover to hold it normally to one side of the tank, and fusible holding means connected with said pivoted means to normally prevent the releasing of the cover.
- 15 3. The combination with a dipping tank having a valved opening and thermostatically controlled means for opening the valve, of inclined rails on opposite sides of the tank, a cover for the tank, standards of different length depending from and connected to the cover and having rollers at their lower ends for slidably supporting the cover upon the rails in horizontal position, and thermostatically controlled means for releasably holding the cover at one side of the tank, whereby the cover may be returned by gravity to close the tank. 20 25 30

FRANK T. SLOAN.
